Patented Nov. 9, 1976

242,199

HANGER

Max Bisk, 1100 Elbridge St., Philadelphia, Pa. 19111

Filed Aug. 20, 1975, Ser. No. 606,374

Term of patent 14 years

Int. Cl. D6—08

U.S. Cl. D6—254

FIG. 1

FIG. 7

FIG. 5 FIG. 6

FIG. 3

FIG. 4

FIG. 1 is an enlarged perspective view of the hanger showing my new design;

FIG. 2 is a front elevational view thereof;

FIG. 3 is a top plan view thereof;

FIG. 4 is a bottom plan view thereof;

FIG. 5 is a side elevational view taken from the left side as seen in FIG. 2; and

FIG. 6 is a side elevational view taken from the right side as seen in FIG. 2; and

FIG. 7 is an enlarged fragmentary perspective view of a second embodiment of the design of FIG. 1, the only difference residing in the support member.

I claim:

The ornamental design for a hanger, as shown and described.
